CLAIM

The ornamental design for an electrical connector receptacle for a printed circuit board, as shown and described.

DESCRIPTION

FIG. 1 is a top plan view of an electrical connector receptacle for a printed circuit board shown an embodiment of my new design;

FIG. 2 is a front elevational view thereof;

FIG. 3 is a bottom plan view thereof;

FIG. 4 is a right side elevational view thereof, the left side elevational view thereof being a mirror image;

FIG. 5 is a rear elevational view thereof; and

FIG. 6 is a cross-sectional view thereof, taken along the line 5—5 in FIG. 2.

FIG. 1

FIG. 2

FIG. 3

FIG. 4

FIG. 5

FIG. 6
